FIREARM

Melvin M. Johnson, Jr., Brookline, Mass., assignor to Melvin M. Johnson, Brookline, Mass., Edward E. Rice, Boston, Mass., and himself, as trustees of Johnson Patent Trust

Application January 5, 1938, Serial No. 183,469

5 Claims. (Cl. 42—4)

In automatic firearms where the breech opens shortly after detonation much difficulty is encountered in extracting shells owing to the expansion of the shells in the firing chamber by gas pressure. The object of the present invention is to overcome this difficulty.

My invention is based on the principle that friction between sliding surfaces can best be overcome by an impact in contradistinction to a steady force. For example if a shell sticks in a firing chamber it can be removed with a ramrod more easily by lightly tapping on the ramrod than by steadily pushing with a heavier force. According to the present invention I provide means for applying to the bolt, at the beginning of each extraction, a sharp blow to the rear, thereby to start the sliding movement of the shell in the chamber. This is accomplished by including, in the breech mechanism, a kicker which recoils relatively to the bolt during the initial stage of recoil and which has a rearwardly-facing abutment for impact against a forwardly-facing abutment on the bolt, the abutments being spaced apart when the bolt is in closed position and the spacing being correlated with the relative movement of said part and bolt to cause the first abutment to impinge against the second abutment when extraction is to be initiated. The aforesaid part preferably comprises a plunger interposed between the bolt and recoil spring which is kicked back in the initial recoil movement of the breech mechanism, preferably by a rotary component of the initial movement of the bolt.

The invention is particularly applicable to firearms of the reciprocating barrel type in which the bolt has locking lugs seating against locking abutments on the barrel, a part of the bolt (either the whole bolt or merely the bolt head) having rotary or other transverse movement to bring the locking lugs into locking engagement with said abutments at the end of the closing movement of the bolt and out of locking engagement in the initial stage of the recoil movement of the bolt. In the preferred embodiment of the invention the aforesaid plunger has a forwardly-facing cam surface engaging a rearwardly-facing cam surface on a lug on the bolt which rotates the bolt into locked position at the forward end of the closing movement of the bolt and which, in the initial stage of bolt recoil, serves to kick the plunger to the rear as aforesaid, thereby to facilitate extraction. Thus the cam lug on the bolt constitutes an actuator which has a transverse (rotary) component of movement at the

forward end of its reciprocation, and the plunger constitutes a kicker which recoils relatively to the bolt in response to said transverse component of movement.

For the purpose of illustration a typical embodiment of the invention is shown in the accompanying drawing in which,

Fig. 1 is a top plan view with parts broken away and parts in section, showing the breech mechanism in closed position;

Fig. 2 is a similar view showing the parts in the positions which they occupy at the moment extraction begins;

Fig. 3 is a similar view showing the parts in the positions which they occupy at the moment of ejection; and

Figs. 4 and 5 are sections on lines 4—4 and 5—5 of Fig. 2.

The particular embodiment of the invention chosen for the purpose of illustration comprises a receiver 1, a barrel comprising two parts 2 and 3 threaded together at 4, a bolt 5, an extractor 6 mounted on the bolt, an ejector 7 mounted in an opening 8 in the side of the receiver, a handle 9 for manually retracting the bolt, the aforesaid plunger or kicker 10, a strut 11 pivotally connected to the rearward end of the plunger 10 by pin 12, the strut 11 extending back to the recoil spring not shown, and a firing pin 13. The rearward end of the barrel sleeve 3 has an annular row of inwardly projecting locking lugs 14 and the forward end of the bolt has an annular row of outwardly projecting locking lugs 15. In the closing movement of the bolt the lugs 15 pass between the lugs 14, after which the bolt is rotated in a counter-clockwise direction (Figs. 4 and 5) to bring the bolt lugs 15 in front of the barrel lugs 14, thereby interlocking the bolt to the barrel. When the gun is fired the bolt and barrel recoil together from the position shown in Fig. 1 to the position shown in Fig. 2, and during this recoil the bolt is rotated, by mechanism hereinafter described, to bring the lugs 15 on the bolt into alignment with the spaces between the lugs 14 on the barrel, whereupon the bolt is free to recoil. After the bolt is disengaged from the barrel the latter may be returned to forward position by a spring (not shown) as described in my Patent No. 2,094,156, granted September 28, 1937, or the barrel may remain in retracted position until the bolt returns to forward position, the barrel then being pushed to its forward position by the bolt after the lugs 15 on the bolt have passed through the spaces between the lugs 14 on the barrel, while the bolt is rotating to

locked position during the final stage of its forward motion.

The rotary movement of the bolt to locked position is controlled by lugs 16 and 17 on the bolt 5 and plunger 10, respectively, the lug 17 having a forwardly-facing cam surface 18 engaging a rearwardly-facing cam surface 19 on the bolt lug 16 tending to rotate the bolt into locked position. Mounted on the lugs 16 and 17 are rollers 10 20 and 21 which fit into a groove in the top of the receiver (Figs. 4 and 5) to prevent rotation of the bolt and plunger during recoil. However, as shown in Fig. 5, the forward end of this groove has a lateral offset to permit rotation of 15 the bolt to locked position at the forward end of its closing movement. To rotate the bolt out of locked position while the bolt and barrel recoil together, the lug 16 is provided with another cam surface 22 engaging a cam surface 23 which 20 is fixed to the receiver. Thus, as the bolt recoils from the position shown in Fig. 1 to the position shown in Fig. 2, the cam surfaces 22 and 23 rotate the bolt sufficiently to bring the lugs 15 on the bolt into alignment with the spaces between the lugs on the receiver. Engagement of 25 the roller 20 with the side of the aforesaid groove of the receiver stops the rotary movement and the bolt continues to the rear by straight-lined movement alone. In the particular embodiment 30 of the invention shown in the drawing the cam surface 23 is formed on a lug 24 depending from a cover plate 25 which is mounted on the receiver by a dovetailed connection 26 (Fig. 5), the cover sliding into the receiver from front to rear 35 and being held in position by a screw 27. The lug 24 seats to the rear against a shoulder 28 in the receiver so that the rearward thrust on the lug by the bolt lug 16 is transmitted directly to the receiver.

According to this invention, the bolt is provided with a forwardly-facing shoulder 29 engageable by the rear end of the lug 17 to facilitate extraction. This shoulder is spaced from the lug 16 on the bolt a distance slightly greater than the length of the lug 17 on the plunger so that at the moment the bolt is unlocked from the barrel (as illustrated in Fig. 2) there is sufficient space for back and forth movement of the lug 17 between the lug 16 and the shoulder 29. 45 This freedom of movement is utilized to facilitate extraction in the following manner: During the initial stage of recoil movement, while the bolt barrel and plunger are recoiling together and the bolt is rotating from locked to unlocked 50 position, the plunger lug 17 is moving to the rear somewhat faster than the bolt because of the camming action between the surfaces 18 and 19 on the lugs 16 and 17 respectively. Furthermore, at the moment the bolt is unlocked from the 55 barrel its rearward component of movement is checked, through the medium of the extractor, by the tendency of the cartridge shell to stick in the firing chamber. Inasmuch as the plunger lug 17 is traveling faster than the bolt and is 60 not checked by the cartridge, it continues to the rear, impinging on the shoulder 29. By virtue of this rearward impact on the bolt at the moment extraction begins the shell is loosened in the firing chamber and the extraction is thereby facilitated. Immediately following this impact the 65 bolt catches up with the plunger because of the resistance of the recoil spring acting on the plunger through the strut 11 and the bolt and plunger then continue to the rear to the position shown in Fig. 3 where the shell is ejected.

The body of the ejector 7 substantially fills the recess 8 in the side of the receiver and the forward end of the projector is provided with a narrow fin 30 on its inner face which engages the shell. The rear end of the ejector lies in 5 a longitudinal groove 31 in the bolt, the forward end of the groove being gradually reduced in depth to cam the ejector into the ejecting position shown in Fig. 3 as the bolt nears the end of its recoil movement. 10

It should be understood that the present disclosure is for the purpose of illustration only and that this invention includes all modifications and equivalents which fall within the scope of the appended claims. 15

I claim:

1. A firearm comprising a bolt, an extractor on the bolt, and breech mechanism permitting automatic recoil of the bolt when the firearm is discharged, said mechanism including a kicker 20 which recoils relatively to the bolt before the bolt leaves the firing chamber and which has a rearwardly-facing abutment for engagement with a forwardly-facing abutment on the bolt, said abutments being spaced apart when the bolt is in closed position and the spacing being correlated with the relative movement of said part and bolt to cause the first abutment to impinge against the second abutment substantially when the bolt leaves the firing chamber thereby 30 to facilitate extraction.

2. A firearm comprising a bolt, an extractor on the bolt, a recoil spring, and breech mechanism normally locking the bolt in firing position and automatically unlocking the bolt when the firearm is discharged, said mechanism including a plunger interposed between the bolt and recoil spring which recoils relatively to the bolt during the initial stage of recoil and which has a rearwardly-facing abutment for engagement with a forwardly-facing abutment on the bolt, said abutments being spaced apart when the bolt is in closed position and the spacing being correlated with the relative movement of said plunger and bolt to cause the first abutment to impinge against the second abutment during said initial 40 stage of recoil thereby to facilitate extraction. 45

3. A firearm comprising a reciprocating bolt having a rotary component of movement at the forward end of its reciprocation, an extractor on the bolt, and automatic breech mechanism controlling the movement of the bolt, said mechanism including a non-rotary kicker which recoils relatively to the bolt during the initial stage of recoil and which has a rearwardly-facing abutment for engagement with a forwardly-facing abutment on the bolt, said abutments being spaced apart when the bolt is in closed position and the spacing being correlated with the relative movement of said part and bolt to cause the first abutment to impinge against the second abutment during said initial stage of recoil thereby to facilitate extraction. 55

4. A firearm comprising a reciprocating bolt, an extractor on the bolt, and breech mechanism permitting automatic recoil of the bolt when the firearm is discharged, said mechanism including an actuator reciprocating with the bolt and also having a transverse component of movement at the forward end of its reciprocation and said mechanism also including a kicker which recoils relatively to the bolt in response to said transverse component of movement and which has a rearwardly-facing abutment for engagement with a forwardly-facing abutment on the bolt, said 70 75

5 abutments being spaced apart when the bolt is in closed position and the spacing being correlated with the relative movement of said bolt and kicker to cause the first abutment to impinge against the second abutment during said initial stage of recoil thereby to facilitate extraction.

10 5. A firearm comprising a receiver, a recoiling barrel, locking abutments on the barrel, a reciprocating bolt having rotary movement at the forward end of its reciprocation, an extractor, locking lugs on the bolt for engagement with said abutments, a recoil spring, and a plunger between the bolt and spring, the bolt and plunger having

cooperating cam surfaces for moving said lugs into locking engagement with said abutments by rotating the bolt at the forward end of its reciprocation, said receiver and bolt having cooperating cam surfaces for rotating the bolt while the bolt and barrel recoil together, thereby disengaging said lugs from said abutments and, through the medium of said first cam surfaces, kicking said plunger to the rear relatively to the bolt, the plunger having a rearwardly-facing surface impacting on a forwardly-facing surface of the bolt 10 for facilitating extraction.
